[57] CLAIM

The ornamental design for a support for a swing, as shown and described.

DESCRIPTION

FIG. 1 is a perspective view of a support for a swing showing my new design;

FIG. 2 is a front elevational view thereof;

FIG. 3 is a rear elevational view thereof;

FIG. 4 is a right side elevational view thereof; the left side elevational view being a mirror image thereof;

FIG. 5 is a top plan view thereof; and,

FIG. 6 is a bottom plan view thereof.

The broken line showing of a swing and support is for illustrative purpose only and forms no part of the claim.

FIG. 1

FIG. 3

FIG. 4

FIG. 2

FIG. 6
